FOLDABLE STRETCHER

George Berrell Leather and William Hastings
Wallbanks, Feltham, England, assignors to
General Aircraft Limited, Feltham, Middlesex,
England

Application March 27, 1944, Serial No. 528,294
In Great Britain September 7, 1942

6 Claims. (Cl. 5—82)

1

The present invention relates to foldable stretchers and stretcher frames.

It is an object of the invention to provide a foldable stretcher in a convenient, practicable, simple and strong form, which can be effectively reduced in overall length and width without in any way impairing the strength and rigidity and general effectiveness as a stretcher. A particular object of the invention is the provision of an arrangement which enables a full-size stretcher to be folded in such form that it can conveniently be stowed into a comparatively small container adapted and arranged to be dropped, preferably suspended by a parachute, from an aircraft.

The present invention consists in a foldable stretcher frame comprising side rails to carry the stretcher canvas, each side rail having at each end a handle pivotable on a transverse axis. A sectional transverse stay foldable about a pivot intermediate its ends is terminally connected at each end to the handles between the free ends of the handles and the pivots connecting the handles and side rails. The handles are foldable through substantially 180° substantially into the horizontal plane of the side rails without projecting beyond them lengthwise, whereas the transverse stays are foldable to permit approach of the side rails for reduction of overall width of the frame.

The stretcher canvas can be secured in position in any convenient manner and it is preferred that the transverse stays shall be adapted and arranged to engage under projecting ends of the side rails to provide support thereat intermediate the outer end of each handle and its transverse pivot.

In order that it may be clearly understood and readily carried into effect, the invention is hereinafter described with reference to the accompanying diagrammatic drawings, of which:

Figure 1 is a plan view of a stretcher according to the invention shown fully extended both laterally and lengthwise ready for carrying a patient;

Figure 2 is a fragmentary plan view showing one end of the stretcher seen in Figure 1 in the process of being laterally reduced in width;

Figure 3 is an inverted view corresponding to Figure 2, but showing the side rails in the position of minimum width with the handles also folded over inwardly to reduce the overall length;

Figure 4 is a section on the line IV—IV of Figure 3;

Figure 5 is an end view looking on the left-hand end of Figure 3;

2

Figure 6 is a detailed end elevation of a leg support, the nature, function and operation of which will be understood from the ensuing description; while

Figure 7 is a fragmentary side elevation to a greatly reduced scale in proportion to the remaining figures showing how either end of the stretcher can be folded up to provide a back rest so that a patient can use the stretcher in a sitting-up position.

Referring more particularly to Figure 1, the improved stretcher includes a main section comprising side rails 11 with canvas support 10 connected thereto. A handle section is connected at each end of the main section and includes handle bars 13 also connected by canvas and connected to the side rails 11 by pivots 12. The pivots 12 are transverse the stretcher, one for each handle bar and engage the ends of the handle bars with the side rails 11, near the ends of the latter so as to leave definite lengths 11' of the side rails beyond the pivots toward the handle sections. The handle sections each include a foldable stay 14 bridging the bars 13 and connected to the bars 13 by tubular pivots 16 extending at right angles to the plane of the stretcher and passing through the bars 13 at points outwardly of the pivots 12 somewhat less than the lengths 11' of the side rails. The stay is made of two separate lengths pivotally connected, as at 15, at an intermediate length of the stay by a member 15 of an angular cross section (L-shape for example) welded or otherwise secured adjacent one end portion to one of the stay members 14 with its opposite end portion arranged and adapted to overlap the adjacent portion of the other stay member, the freely projected right angular flange of the member 15 limiting the play of the stay parts in one direction, substantially with the same effect as in a conventional rule joint.

As shown, the pivotally connected ends of the stay parts are secured to the tubular pivots 16 on the underside of the handle bars, and when the stay members are in extended relation they each underlie the extended lengths 11' of the side rails near the ends thereof. Thus, when the handle sections are extended the ends of the side rails 11 bear on the stay parts to aid in supporting the weight of the patient on the main length of the stretcher, and more securely support the side rails. It is to be further noted that when the stays are broken at their intermediate pivots 15 and moved toward the ends of the stretcher, the respective side rails 11 and also the re-

spective handle bars 13 of each handle section are moved toward each other and tend to collapse or fold the stretcher and in this movement the stay ends ride from beneath the free ends of the lengths 11' of the side rails, freeing the handle sections for free folding over and onto the main section and having yet another and important function to be later referred to. The canvas 10 is attached to the side rails 11 in any convenient manner, for example by stitching or eyeleting and, in preferred constructions, the canvas extends beyond the ends of the side rails 11 for attachment to the handles 13. Where the canvas is so extended it is preferably slotted or cut-away, as indicated at 17, in order to avoid any possibility of the canvas being caught up in the pivots or between the handles 13 and side rails 11 in the folding operation. To strengthen the stretcher longitudinally, straps 18 and 19 are provided and it will be noted that the strap 18 is somewhat longer than the strap 19. That asymmetry in regard to the length of the strap is deliberately devised for a purpose which will later be understood in the description with reference to Figure 4 of the accompanying drawings.

When it is desired to reduce the overall width and length of the stretcher, the first operation is to effect the folding of the transverse stay 14 about its intermediate pivot 15. The stretcher bearer or other attendant, therefore engages the stay 14 in the vicinity of the pivot 15 and pulls it outwardly from one end of the stretcher and the lateral collapsing operation to reduce the overall width of the stretcher frame then proceeds automatically, as clearly seen with reference to Figure 2. It will be appreciated that, whereas Figure 2 is fragmentary and therefore illustrates only one end, the same thing is happening at the other end, although the respective end foldings need not necessarily be performed simultaneously.

Having so effectively reduced the overall width of the stretcher frame that the side rails 11 lie substantially contiguous with only the thickness of the stretcher canvas 10 between them, the next operation is to reduce effectively the overall length which is done by folding over the handles 13 at each end until they lie alongside and in the plane of the side rails 11.

A point which is made clear in Figure 4 is the manner in which the stretcher canvas 10 is passed through between the side rails 11 so that the main part of the sheet lies on the underside of the side rails in the fully folded condition. There is also indicated in Figure 4 the position which the straps 18 and 19 can be caused to take. The strap 18, as was particularly noted in the description with reference to Figure 1, is the longer strap and if that part of the strap 18 which is shown in Figure 1 in dotted lines be pulled out in the folded condition of the stretcher, the slack, due to the fold over of the end portion of the stretcher canvas, is taken up so that the strap virtually takes a bowed formation extending between the slots through which it passes in the canvas. The same thing can be done in regard to the strap 19, but being of lesser length the bowed formation produced by the strap 19 is not so large. Nevertheless, if the strap 18 be wrapped round the folded stretcher and engaged through the loop 19, as shown in chain lines, the straps can be used to provide not only a convenient carrying handle with the stretcher in the folded form, but also to provide some measure of

security for holding the stretcher in the folded form.

Figure 5 merely adds to the description over and above that already dealt with, the feature of providing small supporting feet or legs indicated in Figure 5 by the reference numeral 20. The feet or legs 20 are also seen in Figure 3 and are provided at the four corners of the folded frame.

In Figure 6 there is indicated a convenient form of leg support which may be provided for use in cases where a leg injury requires that the leg be supported with the foot space well above the foot end of the stretcher. Accordingly, the cross-bar 21 has pivotally connected at each end, the lateral support members 22 at the foot of each of which the prong 23 is provided. For mounting the leg support it is convenient to engage the prongs 23 in the tubular pivots 16, which pivots 16 pivotally connect the ends of the transverse stays 14 to their cooperating handles 13. It will be noted from Figure 6 that the natural width between the centres of the prongs 23, with the prongs parallel ready for insertion into the tubular members 16, is slightly greater than the overall width between the centres of the pivots, as indicated by the chain line position of the handle and side rails in the fully extended condition. Such an arrangement involves the necessity for engaging the prongs 23 into the tubular members 16 with the leg supports each moved from its natural position, the arrangement being such that when mounted the lateral supports 22 of the leg support must take up the position indicated in chain lines in Figure 6.

In order to adapt the stretcher for use by sitting-up cases, the handles 13 at the head end can be locked in the upwardly extending condition to provide a back rest. To enable that to be done, let it be assumed that the stretcher is already in the extended condition shown in Figure 1. If then it is required to put the head end as an inclined back rest, as shown in Figure 7, the lateral width of the stretcher frame is reduced to a condition which is just slightly narrower than that shown in Figure 2. In such a position, the folded transverse stay 14 clears the ends 11' of the side rails 11 just sufficiently to enable the handles 13 to be folded up. One back support or handle section is then raised to an inclined position on the pivots 12, and in this movement of the handle section the stays adjacent the pivots 16 are moved into a plane above the ends of the sections 11' of the side rails 11 of the main section. The stays 14 are then moved into spread or operative position to spread the stretcher and the inclined handle section permitted to swing on the pivots 12 until the stay ends rest upon the upper surfaces of the ends 11' of the adjacent side rails of the main section. This holds the inclined handle section at a definite inclination to the main section for service as a back rest. In that position the end of the feet 20 at the head end line up with the inner end of the handle, as indicated at 13A, to support one end of the stretcher above the ground line indicated by the letter G.

To provide the ideal of lightness, the side rails 11, the handles 13, the transverse stays 14, the feet 20 and the leg support where such is provided, are preferably formed of light alloy box section hollow members, but it is in fact quite practicable for the purposes for which the foldable stretcher is provided to form those members from hollow box section steel. The canvas 10 may be

detachable. The straps 18 and 19, which are largely optional, can be attached to the canvas by stitching or in any convenient manner and, although preferably adapted and arranged to pass through slots to leave a substantial portion both above and below the canvas, there is no reason why the straps should not be provided wholly above or wholly below the canvas. The feet likewise are largely optional.

What we claim is:

1. A foldable stretcher frame, including side rails, a handle pivotally connected to each end of each side rail on a horizontal pivot for swinging to operative positions beyond the ends of the side rails or to inoperative positions within the lengths of said side rails, a canvas section secured to said side rails and to said handles, a transverse stay at each end of the lateral side rails and each comprising two parts pivotally connected, the outer ends of the stays being pivotally connected to the handles at the respective ends of the frame on vertical pivots, said canvas being cut away to avoid canvas gripping adjacent the pivotal connections of the handles, the handles when in operative position providing with the lateral side rails an extended stretcher frame and when in inoperative position reducing the overall length of the frame, the stays when moved on their inner pivots reducing the width of the frame.

2. A construction as defined in claim 1, wherein in the handles and side rails are pivotally connected by tubular pivots, and wherein a foot rest is provided for the frame, said foot rest including a cross member and depending members connected to the cross member, said depending members having terminal ends to seat in said tubular pivots to support the cross member in spaced relation above and transverse the frame.

3. A construction as defined in claim 1, wherein longitudinally extending straps are attached at their ends to the canvas, with their intermediate portions free of connection with the canvas, whereby when the structure is reduced in length and width, the free portions of the straps may be drawn upon to take up slack in the straps, to form a tie for the frame, and to mutually interengage to form a carrying handle.

4. A stretcher including a main section including spaced side rails and a handle section including spaced handle bars, a canvas connected to the side rails and to the handle bars, the handle bars being swingingly connected to the side rails, and stays pivotally connected at their ends to the handle bars and each made up of two bars pivotally connected at an intermediate point to cause the

stay bars when aligned to space the side rails and handle bars and when moved on their intermediate pivots to move the respective side rails and the respective handle bars toward each other, the ends of the stay bars when aligned underlying and contacting with the adjacent ends of the side rails to support the main section when the main section and handle section are in substantially horizontal stretcher-forming alignment.

5. A stretcher including a main section including spaced side rails and a handle section including spaced handle bars, a canvas connected to the side rails and to the handle bars, the handle bars being swingingly connected to the side rails, and stays pivotally connected at their ends to the handle bars and each made up of two bars pivotally connected at an intermediate point to cause the stay bars when aligned to space the side rails and handle bars and when moved on their intermediate pivots to move the respective side rails and the respective handle bars toward each other, the ends of the bars of the stays underlying and contacting the ends of the adjacent side rails when the stays are extended and the main and handle sections of the stretcher are in substantial alignment and moved free of such contact when the stays are moved on their intermediate pivots to collapse the stretcher, a handle section being movable into inclined relation to the main section when the associated stay bars are free of the ends of the side rails, the inclined position of a handle section carrying the ends of the stay bars to overlie and contact the ends of the adjacent side rails to prevent movement of the inclined handle section in one direction.

6. A stretcher including a main section of independent side rails, a handle section of independent handle bars pivotally connected to the side rails, and a stay having an intermediate joint to permit extended or folded positions of the stay, the ends of the stay being connected to the handle bars in such relation to the adjacent ends of the side rails that when the handle section is swung upwardly in a substantially similar plane with the main section the ends of the stays will underlie and support the main section, such stay ends when the handle section is at an inclination to the plane of the main section being in a position to overlie and contact the adjacent ends of the side rails to maintain the relatively inclined position of the handle section, and canvas carried by the side rails.

GEORGE BERRELL LEATHER.
